UNITED STATES PATENT OFFICE.

CLIFTON H. IMPSON, OF AUBURN, IOWA.

WORK-SUPPORT FOR FORD ENGINES.

1,219,460.

Specification of Letters Patent. Patented Mar. 20, 1917.

Application filed March 28, 1916, Serial No. 87,228. Renewed February 7, 1917. Serial No. 147,257.

To all whom it may concern:

Be it known that I, CLIFTON H. IMPSON, a citizen of the United States, residing at Auburn, in the county of Sac and State of Iowa, have invented certain new and useful Improvements in Work-Supports for Ford Engines, of which the following is a specification.

My invention relates to work supports, and more particularly to a support for easily receiving and conveniently holding Ford engines while undergoing repairs, being cleaned, etc.

My object is to provide a device, especially for use in garages, adapted to support a Ford engine in such a manner that the engine can be easily swung into any position desired, and when need requires can readily be held or secured in a number of different positions.

Another object is to provide a device of this character adapted to be moved over the floor easily when it is desired to carry the engine from one part of the shop to another, and to set firmly on the floor in frictional engagement therewith when a stationary support for the engine is required.

Other objects will appear in the subjoined description.

My invention includes as principal parts thereof, a bottom, end posts, and side sections, with other minor features, all suitably united together and adapted to conveniently support an engine in a great variety of positions, and to give easy access to any part of the engine or engine block that it may be desired to work on.

The invention consists in certain novel constructions and arrangements of parts herein-after described and claimed, reference being had to the accompanying drawings, in which:

Figure 1 is a side elevation of my improved engine support, showing the block of a Ford engine held thereupon.

Fig. 2 is a transverse section of Fig. 1, on a reduced scale, the section being taken on line 2—2 of said figure, looking in the direction of the arrow.

Fig. 3 is a central, vertical section of one of the end posts.

Fig. 4 is a similar view of the other end post.

Fig. 5 is a vertical section of the device somewhat similar to Fig. 2, and showing a method of supporting the engine block in an approximately horizontal position requiring

one of the side supports only; the other support being thrown down out of the way.

Fig. 6 is a side view of the tie rod.

Fig. 7 is a perspective view of the bottom of the device.

Fig. 8 is a side elevation showing the inner side of one of the side wings or supports of the device.

Fig. 9 is a side elevation of one of the end posts—the one illustrated in Fig. 4.

Fig. 10 is a side elevation of one of the end-post braces.

Fig. 11 is a broken plan view of the bottom of the device showing the caster arrangement, and the stop for the caster rod; 70 and, Fig. 12 is a broken side elevation of the end post illustrated in Fig. 8.

The bottom 1 of my device is formed of the longitudinal bars 2 and 3, and the four transverse bars 4, 5, 6, and 7, secured to the underside of the longitudinal bars 2 and 3 by bolts 8. The transverse bars 4, 5, 6, and 7 are provided on their under faces with recesses 9 (see Fig. 11) for receiving the nuts of these bolts to prevent them from projecting beyond the under faces of said bars into engagement with the floor.

At the ends of the bottom 1 of my engine support are two end posts 10 and 11 hinged thereto, the post 10 being at the transmission end of the engine to be supported and the post 11 at the other end. Each of these posts has a bottom bar 12 and side braces 13. The bottom bars 12 are preferably of the same width as the transverse bars 4 and 7 to which they are connected by means of separable hinges 14. The end post 10 is provided at its top with an opening 15, and in this opening, at the lower side thereof is a bearing 16 adapted to receive one end of the crank-shaft 95 of the engine. This bearing has a flat angular extension 17 for firmly securing the bearing in position on the post. This bearing also has an inwardly projecting end 18 adapted to be received into the annular groove of the drum at the transmission end of the engine.

The end post 11 differs slightly from the post 10 in that it does not have an opening in the upper end thereof, but has the bearing 19 for the crank-shaft mounted on top of the post, the post being of a height to bring the bearing 19 into the same horizontal plane or level with the bearing 18 of the other post. The bearing 19 also has a flat angular exten-

60

105

110

sion 20 similar to the extension 17 of the bearing 16. The bearing 19 also has an inwardly extending end 21 which is simply intended to increase the area of the bearing.

5 The angular extensions 17 and 20 of the bearings 16 and 19 lie in flat engagement with the inner faces of the posts, immediately underneath said bearings, and are provided with suitable openings for the screws 22 which take through said openings into the end posts to firmly secure the bearings in position thereon. The end posts 10 and 11 are provided near their centers with similar openings 23. These openings 15 have their under sides inclined and are reinforced at the outer sides of the posts by the metallic plates 25 which have inwardly-struck portions 26 fitting the inclined under sides of the openings 23. The similar braces 27 and 28 for the end posts 10 and 11, are secured at their inner ends by bolts 29 (Fig. 10) to the transverse bars 5 and 6, respectively, of the bottom 1. At their upper ends they are provided with spring 25 latches 30 and 31 respectively. These latches have projecting ends 32 and 33 which are inclined on their under sides and provided at the inner ends of their inclines with shoulders 34 and 35. When the end posts 30 10 and 11 are swung up into vertical position, their inner sides will abut against the outer ends of the braces 27 and 28 and the brace latches 32 and 33 will pass through the openings 23 of the posts, riding up over 35 the inclined bottoms 26 of said openings, and the shoulders 34 and 35 of the latches will engage the metallic plates 25 on the outer faces of the end posts. Being engaged in this way, the end posts are rigidly 40 held in their vertical position against movement in either direction.

At the sides of the bottom 1 of my device are the two similar side supports 36 and 37, each of which has a bottom bar 38 and a 45 top bar 39 and side bars 40, any of which parts may be formed of angle iron when desired, especially the side bars 40 which are shown in the drawings as thus formed. Secured to the bottoms of the side supports 50 36 and 37 are sections of separable hinges 41 by which these supports are hinged to the longitudinal bars 2 and 3 of the bottom 1 of the device, to swing upwardly and downwardly thereupon. The lower ends of 55 these side supports are inclined as at 42 to permit the supports to swing upwardly toward each other beyond the vertical, and their tops are correspondingly inclined as at 43 to bring the faces of said top ends 60 into a substantially horizontal plane when the supports are at their inward position. Toward their upper ends these side supports 36 and 37 are provided with the similar transverse brace rods 44 and 45, and loosely 65 mounted on these rods are the braces 46

and 47 respectively, the braces 47 being longer than the braces 46. These braces are employed to engage the engine block when it is to be firmly held in the position illustrated in Fig. 2.

70 The tie rod 48 illustrated in Fig. 6 engages the brace rods 44 and 45 to hold the upper ends of the sides 36 and 37, and the braces 46 and 47 carried thereon, in firm engagement with the engine block when it 75 is desired to hold the same in the position illustrated in Fig. 2. This rod is provided at one end with the hook 49, and at its other end is threaded and bent downwardly, the threaded end being provided with a wing 80 nut 50 and a block 51 carrying a hook 52, the block being loosely mounted on the threaded portion of the rod just above the wing nut and adapted to coöperate therewith, the hook 49 engaging one of the brace 85 rods 44 or 45 and the hook 52 engaging the other.

80 The bottom 1 of my device is provided with the casters 53, mounted on the transverse rod 54 which is rendered eccentric by means of the bends 55. The rod 54 terminates at one end in a bent section 56 which forms a handle lever for partially rotating said rod to throw the casters down sufficiently to cause them to project beyond the 90 under face of the bottom 1 to engage the floor, which adapts the device to be rolled over the floor on the casters when it is desired to move it from place to place either empty or with an engine supported 100 thereupon. The casters are somewhat nearer to one end of the frame than the other so that a part of the bottom will always be in frictional contact with the floor to normally prevent too free a movement 105 of the support over the floor; but, when in moving the device over the floor, it is desired to support the whole weight of the frame upon the casters, it is only necessary to hold the bottom in an approximately 110 horizontal position. The stop block 57 is arranged to engage one of the bends 55 of the rod 54 when the casters are moved downwardly to their proper operative position. The keeper 58 is secured to the bottom 115 of the device by screws 59 and is adapted to engage the lever 56 to hold the casters in their downward position.

120 The hinges 44 and 41 of the device are all provided with similar hinge pins 60 (Fig. 1), so that the end posts 10 and 11 and the sides 36 and 37 can be quickly detached from the bottom when it is desired to take the device apart for shipping. These hinge pins are all interchangeable 125 with each other to facilitate the setting up of the device.

130 It will be seen at a glance that when the sides and ends are disconnected from the bottom, the whole device is adapted to form a

comparatively small and compact package for shipping.

When it is desired to set the device up again after it has been taken apart, all that is required is to secure the sides and ends in position (with the hinge pins 60), and the braces 27 and 28 by means of the bolts 29.

The end posts 10 and 11 are spaced from each other a distance adapting them to engage the ends of the crank-shaft 61 of the engine (see Fig. 1), which is really the only place that the engine can be engaged to be handled easily. But being engaged in this way, it can be readily swung into any position desired with one hand.

The side supports 36 and 37 are nearer to one end of the device than the other in order to bring them about the center of the weight of the engine.

The operation of the device is apparent, in many respects, from what has already been set forth, but it will be well to here point out some of the uses of the device, which might, in greater or less degree, be overlooked.

(1). The whole engine and crank case can be taken out of the car and set in the stand for disassembling. In doing this it is only necessary to lower the end post 10, which permits the engine to be easily set in place on the stand; then the end post is brought back to its vertical position which brings the transmission end of the crank shaft through the opening 15 at the upper end of the post, into engagement with the bearing 16 in said opening. As soon as the post reaches its vertical position it is engaged by the spring latch 30 which securely holds it in that position.

(2). No bolts or screws are needed to fasten the engine in the stand.

(3). By leaving the side supports up with the engine supported on them, the end posts can be let down and the engine taken all apart with nothing left but the block 62. When it is desired to work on the transmission, magnets, fly wheel, etc., the post 10 is let down; and when on the gears, timer, etc., the other end 11 is let down. In this way all the parts of the engine are easily and conveniently got at, and no part is inaccessible or inconvenient of access.

(4). The engine can be swung into any position desired to enable one to work on it to the best advantage. This is specially convenient in working out the bearings as you work them out, and can be done either from a belt connecting the line shaft with the transmission drums 63 or by means of a universal joint connection from any suitable source of power connected up with the engine through the hole 15 in the upper end of the post.

In tightening up the bearings and working them out I arrange the stand and block

as illustrated in Figs. 1 and 2—with the ends and sides all up; with the tie rod 48 passing through the center opening 64 of the block, engaging the brace rods 44 and 45 drawing the sides 36 and 37 together with the braces 46 and 47 into firm engagement with the block, by which combined means the block is held very rigid. The wing nut 50 and the hook 52 on the tie rod make this rod very easy to connect up.

(5). In valve grinding, carbon removing, and taking the pistons out, the parts are arranged as illustrated in Fig. 5, with the block swung over to rest on one of the side supports and the other support let down out of the way. The block is, of course, supported on whichever side of the device may be desired. When it is desired to support the block in a vertical position with the head 65 of the block upward, the block is swung into the desired position, and the two sides 36 and 37 are put up and connected together by the brace rod 48, and the engine is then held in this position by the top ends of the two sides. In Fig. 2 the block is held in the reverse position with the head 65 of the block downward and the flanges 66 of the block resting on the top ends of the sides 36 and 37. The engine is very reliably supported by these two sides so that either one or both of the end posts 10 and 11 may be let down whenever need requires.

(6). By means of the casters which are controlled by the lever 56, the device can be quickly converted into a carriage which may be run up by the side of the car to receive the engine and take it to the work bench, or wherever else it may be desired to work on it before the repairs are finished, and then to return with it again to the car when the work is done.

Extensive practical use of the device has proven it to be a great success, since an engine can be most conveniently handled by it and brought into any desired position with great ease, and without the least danger of letting it fall.

Having thus described my invention, what I claim as new and desire to secure by Letters Patent is:—

1. In a device of the character described, a bottom; end posts hinged to the bottom to swing up and down thereon, and spaced apart a distance to adapt them to engage the ends of the crank-shaft of an engine to be supported, said end posts having bearings for receiving said ends of the crank-shaft; braces secured at their inner ends to said bottom and held rigid against longitudinal movement thereon, and extending upwardly and outwardly toward said end posts to form abutments therefor when the end posts are swung into operative position; and means for locking said posts in rigid engagement with said abutments.

2. In a device of the character described, a bottom; end posts hinged to the bottom to swing up and down thereon, and spaced apart a distance to adapt them to engage the ends of the crank-shaft of an engine to be supported, said end posts having bearings for receiving said ends of the crank-shaft; braces rigidly secured at their inner ends to said bottom and extending upwardly and outwardly toward said end posts to form abutments therefor when the posts are swung into operative position; and connections at the outer ends of said braces for automatically engaging and interlocking with said posts to rigidly hold the same in operative position.
3. In a device of the character described, a bottom; side supports hinged thereto to swing up and down thereon and adapted to engage an engine to support the same; and adjustable means for engaging said supports to hold them in operative relation to each other and in engagement with the engine at the two sides thereof.
4. In a device of the character described, a bottom; side supports hinged thereto to swing up and down thereon and adapted to engage an engine to support the same; adjustable means for engaging said supports to hold them in operative relation to each other and in engagement with the engine at the two sides thereof; and braces carried by said supports for engaging the sides of the engine below where it is engaged by the supports proper.
5. In a device of the character described, a bottom having side supports hinged thereto to swing up and down thereon and adapted to incline inwardly toward each other from bottom to top, when in operative position, to bring the top ends of the supports in position to engage the sides of an engine underneath the flange thereof; brace rods on said supports below the upper ends thereof; braces carried on said rods for engaging the sides of the engine below where it is engaged by the supports proper; and an adjustable tie rod adapted to pass through the center opening of the block of the engine and to engage the two brace rods carried by the supports, to adjustably secure the supports and braces in engagement with the engine.
6. In a device of the character described, a bottom; end posts hinged thereto to swing up and down thereon, and spaced apart a distance to adapt them to engage the ends of the crank-shaft of an engine to be supported; means for engaging and holding the posts when swung into operative position;

side supports also hinged to the bottom to swing up and down thereon and adapted to engage the engine underneath the flanges at the sides thereof to assist in supporting the same; and means for engaging said supports to hold them in engagement with the sides of the engine.

7. In a device of the character described, a bottom; end posts hinged thereto to swing up and down thereon, and spaced apart a distance to adapt them to engage the ends of the crank-shaft of an engine to be supported; means for engaging and holding the posts when swung into operative position; side supports also hinged to the bottom to swing up and down thereon and adapted to engage the engine underneath the flanges at the sides thereof; casters on the bottom of the device; and means for throwing the same into or out of engagement with the floor at the will of the operator, whereby to support the weight of the device upon the casters when it is desired to move it over the floor, and to support it rigidly upon its bottom as if it had no casters, at other times.

8. In a device of the character described, a bottom; end posts hinged thereto to swing up and down thereon and spaced apart a distance to adapt them to engage the ends of the crank-shaft of an engine to be supported; braces adapted to form abutments for the posts when swung upwardly into a vertical position; latches for engaging and holding the posts when they come into engagement with the braces; side supports also hinged to the bottom to swing up and down thereon and adapted to incline inwardly toward each other from bottom to top when in operative position, to bring the top ends of the supports into position to engage the sides of the engine underneath the flange thereof to assist in supporting the engine; brace rods on said supports below the upper ends thereof; braces carried on said rods for engaging the sides of the engine below where it is engaged by the supports proper; and an adjustable tie rod adapted to pass through the center opening of the block of the engine and to engage the two brace rods carried by the supports, to adjustably secure the supports and braces in engagement with the engine.

In testimony whereof I affix my signature in the presence of two witnesses.
